UNITED STATES PATENT OFFICE.

JACOB J. PLUCKER, OF PHILADELPHIA, PENNSYLVANIA.

DESIGN FOR A WALL-COVERING.

No. 38,588.

Specification for Design.

Patented May 28, 1907.

Application filed April 19, 1907. Serial No. 369,182. Term of patent 7 years.

To all whom it may concern:

Be it known that I, JACOB J. PLUCKER, a citizen of the United States, residing at Philadelphia, in the county of Philadelphia and State of Pennsylvania, have invented a new, original, and ornamental Design for Wall-Coverings, of which the following is a specification, reference being had to the accompanying drawing, forming a part thereof.

The figure is an elevation of a wall covering, showing my new design.

I claim:

The ornamental design for a wall covering, as shown.

JACOB J. PLUCKER.
